UNITED STATES PATENT OFFICE

2,416,026

BILLFOLD

Lester L. Sherwood, Los Angeles, Calif.

Application June 12, 1943, Serial No. 490,603

2 Claims. (Cl. 150—38)

1

My invention relates to a pocket bill fold adapted to contain paper currency, checks, business cards, stamps, license and identification cards, and the like, and the principal objects of my invention are, to provide a simple, practical and inexpensive bill fold which is devoid of all stitching, or fastening means of metal, plastics and the like, and further, to provide a bill fold wherein the main body portion and the side and end flaps which co-operate with the body portion and with each other in forming pockets, are composed of a single piece of leather or like thin flexible material.

A further object of my invention is to provide a bill fold of the character referred to, which includes separately formed flexible members, adapted to be detachably connected to parts of the bill fold to serve as a closure for the ends of certain of the pockets therein, also for receiving and conveniently holding transparent envelopes which may contain license and identification cards.

With the foregoing and other objects in view, my invention consists in certain novel features of construction and arrangement of parts which will be hereinafter more fully described and claimed and illustrated in the accompanying drawings in which:

Fig. 1 is a view of the body of the bill fold in open unfolded condition.

Fig. 2 is an elevational view of the bill fold in partially open condition.

Fig. 3 is a horizontal section taken on the line 3—3 of Fig. 2.

Fig. 4 is a horizontal section of a portion of a modified form of the bill fold and showing the detachable pocket end closing member applied thereto.

Fig. 5 is a view of the pocket end closing member in unfolded condition.

Fig. 6 is a vertical section taken on the line 6—6 of Fig. 2.

Fig. 7 is a view of the detachable transparent envelope carrying member in open unfolded condition.

Fig. 8 is a detail view of the corner of one of the transparent envelopes.

Fig. 9 is a detail section of a portion of the envelope carrier and showing a pair of envelopes attached thereto.

Fig. 10 is an elevational view of a portion of the bill fold in open condition and showing the envelope carrier applied thereto.

Fig. 11 is a horizontal section showing the en-

2

velope carrier connected to the bill fold so as to be quickly removed therefrom.

Fig. 12 is a sectional view similar to Fig. 11 and showing the envelope carrier connected to the bill fold by one of the leather buckles and its strap.

Referring by numerals to the accompanying drawings which illustrate a preferred embodiment of my invention, 10 designates the main body of the bill fold which is composed of leather or other thin flexible material, and said body is cut to form a rectangular outer wall 11, an outer wall lining 12, foldable on the dotted line a, pocket forming walls 13 foldable on the dotted lines b, pocket forming walls 14, foldable on the dotted lines c, and flaps 15 and 15a integral with walls 14, and foldable on the dotted lines d.

Flap 15 is provided with a square aperture 16 for the reception of a leather buckle, and flap 15a is provided with a pair of square buckle receiving apertures 17.

Formed integral with the lower edge of outer wall 11 are flaps 18 and 18a, foldable on the dotted lines e and between these flaps is a small

25 reinforcing flap 19, which when the bill fold is made up, is folded upwardly and cemented to the inner face of outer wall 11 as illustrated by dotted lines f.

Flap 18 is provided with a pair of horizontally disposed slits 20 for the reception of parts of a leather buckle and flap 18a is provided with two pairs of similar slits 21.

When the main body of the bill fold is made up, lining wall 12 is folded downwardly onto the inner face of outer wall 11 and the space between said walls forms a secret pocket 22 for the reception of paper currency, valuable papers and the like.

Walls 14 are now folded upwardly onto walls

40 13 and the latter are now folded inwardly onto the end portions of lining wall 12 with walls 14 between said walls 13 and the lining wall. A rectangular connector wall 23 of leather or the like and smaller in dimensions than outer wall 11, has its end portions inserted between walls 14 and 13 and the spaces between said walls form pockets for the reception of cards, stamps, folded note papers and the like.

The central portion of wall 23 bridges the 50 space between the inner edges of the pocket forming walls 13 and 14 (see Figs. 2 and 3).

Buckles 24 of leather or the like and having integral straps 25, are detachably engaged in the pairs of slits 20 and 21, said buckles being disposed on the inner faces of the flaps 18, 18a and

the latter are folded upwardly onto the outer faces of the walls 13. After the folds 15 and 15a have been folded downward onto the outer faces of flaps 13, the projecting portions of the buckles are inserted through the apertures 16 and 17 and 5 straps 25 which depend from the buckles behind said flaps 15 and 15a, are now drawn upward on the outer faces of said flaps and inserted through those portions of the buckles which project through openings 16 and 17, thus securing the 10 flaps in closed positions (see Fig. 2).

The leather buckles and straps utilized in my improved bill fold are identical with those illustrated and described in my co-pending application for U. S. Letters Patent filed February 15, 1943, Ser. No. 476,554, now Patent No. 2,388,444, issued November 6, 1945.

In some instances, it may be found desirable to dispense with the connector wall 23 and to provide pockets between the wall 14 and right hand portion of lining wall 12, and in such case, a rectangular wall 26 of leather or the like is positioned between said walls 12 and 14 and a flap 27 on the left hand end of said wall 26 is bent rearwardly so as to occupy a position between 25 wall 13 and flap 18a (see Figs. 4 and 5).

This flap is provided with spaced parallel slits 28 for the accommodation of parts of the left hand one of the leather buckles which united flaps 15a and 18a.

Thus a pocket 29, closed at both ends and bottom and open at its top, is formed between the walls 14 and 26 and a pocket 30 open at top and left hand end and closed at bottom and right hand end, is provided between wall 26 and the right hand portion of lining wall 12.

Pocket 29 being closed on three sides provides a convenient and fairly safe receptacle for coins. In Figs. 7 to 12 inclusive I have shown means for carrying in the bill fold, one or more transparent envelopes adapted to contain license cards, personal identification cards and the like and such means consists of a rectangular section 31 of flexible material such as leather provided at its right hand end with a flap 32, foldable on the dotted line *h* and formed in said member 31 near its left hand end are pairs of slits 33.

The material between said slits provides narrow flexible strips 34 which are adapted to pass through substantially T-shaped slots 35 formed in the ends of transparent envelopes 36 (see Figs. 8 and 9).

This envelope carrier may be associated with the bill fold so as to be readily removed therefrom to exhibit the cards or certificates contained in the envelopes, by placing said carrier between flap 18 and wall 13, with the right hand end of member 31 folded over the adjacent ends of the envelopes and with flap 32 positioned between the right hand end of wall 13 and connector wall 23 (see Fig. 11).

In Fig. 12 the envelope carrier is shown detachably connected to flap 18. Where such arrangement is carried out, the center of member 31 is provided with a pair of slits 37 for the reception of parts of the leather buckle that is associated with the flaps 15 and 18.

Thus it will be seen that I have provided a bill fold which is simple in construction, inexpensive

of manufacture, entirely devoid of stitching or other fastening and securing means and very effective in performing the functions for which it is intended.

It will be understood that minor changes in the size, form and construction of the various parts of my improved bill fold may be made and substituted for those herein shown and described, without departing from the spirit of the invention, the scope of which is set forth in the appended claims.

I claim as my invention:

1. A bill fold body formed from a single piece of thin flexible material and comprising an outer wall, a lining member integral with the upper edge of said outer wall, pocket forming walls integral with the ends of said outer wall, pocket forming walls integral with the lower edges of said first mentioned pocket forming walls, flaps integral with the lower edges of said second mentioned pocket forming walls for closing the upper ends of the pockets formed by said pocket forming walls, spaced flaps integral with the lower edge of said outer wall and foldable into position beneath said first mentioned flaps said second mentioned flaps being provided with pairs of slits and flexible means including a keeper and strap detachably seated in the slits in said second mentioned flaps and passing through and partially across the outer faces of said first mentioned flaps for securing them in pocket closing positions.

2. In a bill fold the combination with a body formed from a single piece of thin flexible material and comprising an outer wall, a lining member integral with the upper edge of said outer wall, pocket forming walls integral with the lower edges of said outer wall, pocket forming walls integral with the ends of said outer wall, pocket forming walls integral with the lower edges of said first mentioned pocket forming walls, pocket closing flaps integral with the lower edges of said second mentioned pocket forming walls, said flaps being provided with apertures, and spaced flaps integral with the lower edge of said outer wall and provided with pairs of slits, which when the pocket forming walls and flaps are folded, coincide with the apertures in said pocket closing flaps, flexible loops which pass through said slits and apertures and straps integral with said loops for passing through the latter outside the flaps having the apertures, for detachably securing said flaps to one another.

LESTER L. SHERWOOD.
